UNITED STATES PATENT OFFICE.

WILLIAM W. WILSON, OF LOS ANGELES, CALIFORNIA.

WELL-BORING APPARATUS.

1,195,544.

Specification of Letters Patent. Patented Aug. 22, 1916.

Application filed May 29, 1914. Serial No. 841,735.

To all whom it may concern:

Be it known that I, WILLIAM W. WILSON, a citizen of the United States, residing at Los Angeles, in the county of Los Angeles and State of California, have invented new and useful Improvements in Well-Boring Apparatus, of which the following is a specification.

This invention relates to the art of well boring or well drilling, and more particularly to well borers such as are provided with rotary tops or master wheels whereby the rotation of the boring tool or string of pipe or the like extending upwardly from the same to the rig is caused, such rig being employed in raising and lowering the boring tool and string in performing the operations incidental to drilling.

In United States Letters Patent No. 1,064,270, issued June 10, 1913, to Arthur G. Willard and Charles E. Wilcox, for well boring apparatus, a combination of parts and features is disclosed constituting the well boring apparatus to which the present invention more particularly relates. In this patent separate means of operative connection are disclosed for application to the string, and to the rotary top or table, each in substitution for the other, and whereby the string may be either rotated in couple with the table or held in any particular point of elevation; means being provided upon the string for withdrawing the rotation imparting means upon the elevation of the string so as to permit the other means of operative connection to be substituted therefor between the string and the table, holding up the string during the making-up or breaking-up of the same, as by the addition or withdrawal of further joints or sections of pipe or tubing. That patent refers to the use of devices known as slips for temporarily holding a string of pipe or the like at any particular point of elevation.

In accordance with the present invention, and as an improvement upon or departure from or further specific development of the invention of said prior patent, I provide, for use under conditions making the same advantageous or preferable, a combination of features comprising such slips or the like; and means independent of the table between which and the string the slips are disposed to hold up the string, and likewise to hold up the drive bushing or rotation imparting means; and such slips are disposed, in use,

in the working location of the rotation imparting means, in substitution therefor, or disposed at a point more or less remote from the zone within which the rotation imparting means act. At any rate, the combination of features comprising the present invention contemplates the application of the slips or means of operative connection for holding up the string, during the making-up or breaking-up of the same, between the string and features of installation independent of the rotating top or table or master wheel.

With the above and other general objects and characteristics in view and entering into the invention, the invention consists in the novel and useful provision, formation, construction, combination and association of parts, members and features, all as herein-after described, shown in the drawings, and finally pointed out in claim.

In the drawings: Figure 1 is a vertical sectional view of well boring apparatus provided with the features of improvement constituting the invention, parts being in elevation, the rotation imparting means being shown elevated by means upon the string, and the string and rotation imparting means being shown held so elevated by the other means of operative connection, or slips; Fig. 2 is a transverse sectional view taken upon the line x^2-x^2 , Fig. 1, and looking in the direction of the appended arrows; Fig. 3 is a view similar to Fig. 1, the rotation imparting means being shown in position and the other means of operative connection, or slips, having been removed; parts shown in Fig. 1 being omitted and parts sectioned for clearness of illustration; Fig. 4 is a detail transverse sectional view, taken upon the line x^4-x^4 , Fig. 3, and looking in the direction of the appended arrows; Fig. 5 is a view similar to Fig. 1, of a modified form of provision, construction, arrangement and combination of parts, members and features; and Fig. 6 is a detail transverse sectional view taken on the line x^6-x^6 , Fig. 1, and looking in the direction of the appended arrows. Figs. 2, 4 and 6 are upon a diminished scale.

Corresponding parts in all the figures are designated by the same reference characters.

Referring with particularity to the drawings, and to Figs. 1 to 4 and 6 thereof, A designates a rotary top or table shown as supported rotatively, by anti-friction rollers

or the like 7, upon a base or frame B, *d* designating suggestively any preferred type or organization of means for imparting rotation to the table; all in accordance with standard or preferred practice. The frame 5 B is shown as having a vertical bore or opening *b* provided in an annular upward extension 8 of the base or frame B, which fits within the annular top or table A which latter rotatively surrounds such extension 8. 10 C designates the mouth of the well hole within which the boring operation is to be performed by a suitable boring tool (not shown) connected with and operated by the string of which the pipe section D is a part; 15 another string portion being shown at E and connected with the string portion or pipe section D by a collar or the like F and which may constitute means upon the string for elevating the rotation imparting means 20 G upon the elevation of the string. In the specific form of construction and combination of features shown in the drawings the rotation imparting means G is directly engaged and elevated by the string member 25 E which constitutes a driving stem for the boring string.

g designates interlocking means whereby the means of operative connection or rotation imparting means G may be coupled with the rotating top or table A so as to impart the rotation thereof to the string. H designates the other means of operative connection adapted to be applied to the string, 30 as to the joint or portion D, to suspend the weight of the same and hold up the string after the withdrawal of the rotation imparting means which is produced upon the elevation of the string; to the end that the string may be broken up, or that other joints or sections may be added thereto, in accordance with the requirements of the drilling operation from time to time. These means 35 H are shown as comprising slips *h* which are introduced between the annular or tubular extension 8 of the base or frame B and the string, such as the joint or member D thereof.

The string member or driving stem E is shown as having a longitudinal bore or duct 40 whereby circulation may be maintained through the same and the remaining portion of the string for the usual purposes in drilling operations; and as having further lateral channels 11 with which interlock 45 tongues 12 upon the bushing 13 constituting the means of operative connection G, the channels 11 being interrupted slightly above the bottom of the stem E; pins 14 being adapted to be passed through a top flange 13^a upon the bushing 13 and into holes or 50 openings 15^a in the table, to constitute the interlocking devices or means *g*. The stem or string member E is free to play vertically 55 through the bushing 13, while in rotative 60

couple through such bushing with the table A.

The slips *h* readily engage with and support the string by impingement of serrations 70 15 or the like upon the outer surface of the string member or joint, so that the string may be held at any desired point of elevation, such impingement being effective at any portion of the section or joint.

The bushing 13^a is shown as formed in 75 separate parts which may be bolted together at flanges 13^b, and by bolts 13^c, to permit of assemblage; the channels 11 terminating slightly above the lower end of the stem E, so that the drive bushing may be lifted out by the tongues 12 thereof, upon the elevation 80 of the string as above set forth.

When the drive bushing and string have 85 been suitably elevated, the slips *h* are introduced into the space between the string and the tubular or annular extension 8 of the base B, as shown in Fig. 1, such slips preferably tapering in thickness downwardly, the outer walls of the same and the inner wall of the tubular extension 8 being complementarily formed, as at 16, the taper of the slips being produced by inclining the outer walls of the slips, the inner serrated walls having together a cylindrical formation or extension vertically. After the string has been 90 lengthened or shortened, by adding or subtracting a joint or member or joints or members, the slips are withdrawn from their working position and the rig is operated to lower the string, permitting the drive bushing 13 to come into position for interlocking 95 again with the rotary table; whereupon the drilling operation may be continued.

Referring to Figs. 5 and 6, the same provision and general combination and association of parts and features is shown as in 100 Figs. 1 to 4 inclusive, with the exception that the base or frame K is not provided with any tubular or annular extension such as shown in the other figures; and the slips 105 *h* constituting the means of operative connection H are shown as applied to the string member D and to a support L which is mounted upon a frame or base M upon 110 which the base or frame K is superposed; both frames K and M being mounted at the mouth of the well hole C. Uprights or frame members 17 support the frame K above the frame M. The mode of use and method of operation and advantages are the 115 same with respect to this modified form of construction and organization, with the exception that instead of applying the slips directly at or to the frame which directly supports the rotary top or table, such slips 120 or means of operative connection H are applied at a point more or less remote from such table-supporting frame, and to a frame or support L distinct and separate from the frame or support K upon which the table 125 130

is directly carried and rotated. Thus, in this modified form of construction and organization, the slips are utilized in a working zone entirely distinct from and more or less remote from the working zone of the means G or the operative connection comprising the drive bushing 13.

In accordance with the present invention, the weight of the string is not imposed upon the table or master wheel through the slips, but is directly imparted to the frame which supports the table or to some other frame or structural feature, without transmission through the table.

It is manifest that many variations and modifications may be made, with respect to the showing in the drawings, and the specific description in the specification, without departing from a fair interpretation of the invention.

Having thus disclosed my invention, I claim and desire to secure by Letters Patent:

In improvements of the character disclosed, the combination, with a rotary table, and a boring string; of means for supporting the string adapted to engage the same at any point of its length and to so support the string independently of the table; said table being provided with a base upon which the table is rotatively supported; said means for supporting the string being applied to the string and to said base; said string supporting means consisting of slips.

In testimony whereof, I have signed my name to this specification in the presence of two subscribing witnesses.

WILLIAM W. WILSON.
